UNITED STATES PATENT OFFICE.

WILLIAM R. WARNER, OF PHILADELPHIA, PENNSYLVANIA.

DESIGN FOR A WIRE STAND.

SPECIFICATION forming part of Design No. 16,533, dated February 16, 1886.

Application filed December 24, 1885. Serial No. 186,661. Term of patent 14 years.

To all whom it may concern:

Be it known that I, WILLIAM R. WARNER, a citizen of the United States, residing in Philadelphia, Pennsylvania, have invented a new and original Design for a Wire Stand, of which the following is a specification.

My design for a wire stand for bottles is fully illustrated in the perspective view of the accompanying drawing.

My design comprises two side pieces, A and A', of open squares *a*, with their corners adjoining and rising one above the other. Running from one side of said squares to the other are a number of horizontal bars, B B' B''. The bars B extend from the bottom pieces of the open squares *a* of one side frame to the bottom piece of corresponding open squares *a* of the other side piece, while the bars B' and B'' run from the vertical sides of the squares *a* on one side to the squares *a* on the other side. A series of ring-like loops, C, extend from the top parts of the squares on one side to correspond-

ing squares on the other side. A horizontal bar, F, is at the top of the side frames, and has upwardly-projecting pieces *f*. There is 25 also a leg, D, at the rear of the stand, and a brace, E; but these two features form no part of my present design, the essential feature of which is the square like form of the side pieces.

I claim—

The herein described design for a wirestand, comprising opposite side frames consisting of adjoining open squares rising one above the other, with cross-bars B B' B'', and looped pieces C, all substantially as shown and described. 30 35

In testimony whereof I have signed my name to this specification in the presence of two subscribing witnesses.

WILLIAM R. WARNER.
